UNITED STATES PATENT OFFICE.

ALFRED WÄCHTER, OF ZURICH, SWITZERLAND.

VANE-WHEEL PUMP.

1,086,488.

Specification of Letters Patent. Patented Feb. 10, 1914.

Application filed November 18, 1911. Serial No. 660,983.

To all whom it may concern:

Be it known that I, ALFRED WÄCHTER, a citizen of Switzerland, residing at 78 Wiedingstrasse, Zurich, Switzerland, have invented new and useful Improvements in Vane-Wheel Pumps, of which the following is a specification.

The present invention relates to a vane wheel pump in which in a pump casing 10 flexible vanes are attached to the inside of a driven drum and to a cylinder which rotates within the latter and eccentrically thereto. At each revolution of the drum therefore the distance of the points of attachment of the vanes between the drum and the cylinder will be successively increased 15 and decreased.

In the drawing is shown by way of example a constructional form of the vane 20 wheel pump, Figure 1 being a section on the line C—C of Fig. 2 and Fig. 2 a section on the line A—A of Fig. 1.

1 is a pump casing which has two connecting branches 2 for the joining on of a 25 supply and discharge pipe respectively. In the pump casing is mounted a revolving cylindrical drum 3, which is closed in at the sides and is concentric with a shaft 4. The drum has in its periphery holes 5, which are 30 separated from each other by ribs 6 mounted parallel to the axis of the drum. The shaft 4 is driven from any source of power.

Mounted upon a cranked shaft 8 inside the drum 3 and eccentrically thereto is a 35 cylinder 7 which approximately fills up the entire width of the drum. The shaft 8 is stationary. Between the wall of the cylinder 7 and the drum 3 are attached vanes 9 made of flexible material which are attached 40 by one end to the ribs 6 of the drum and have their other ends clamped fast in slots provided in the wall of the cylinder 7 and parallel to the shaft 8.

When the cylinder 3 is rotated, the vanes act as drivers for the cylinder 7, so that it 45 likewise has to partake of the rotation in the same direction. At the same time the distance between the points of attachment of the vanes between the drum and the cylinder are increased and decreased at every rotation in consequence of the eccentric mounting of the drum. When the distances are increased air is taken into the space between the vanes through the holes 5 and afterward forced out again when the distances of the 55 points of attachment of the vanes between the drum and the cylinder are decreased, so that it can be carried away through a suitably provided pipe.

I claim:

1. In a vane wheel pump, a drum casing, an outer driven drum closed on both sides rotating within said casing, holes separated by ribs provided around the periphery of said drum, a stationary cranked shaft 35 mounted eccentrically within said drum, a rotating cylinder mounted on said cranked shaft, and flexible vanes each secured at one end to the driven drum and at the other end to the cylinder.
2. In a vane wheel pump, a drum rotating within a drum casing, flexible vanes each secured at their outer ends to said drum, an inner cylinder mounted on a stationary cranked shaft arranged eccentrically within said drum, and slots in said inner cylinder for clamping the inner ends of said vanes.

In testimony whereof I have signed my name to this specification in the presence of two subscribing witnesses.

ALFRED WÄCHTER.
